UNITED STATES PATENT OFFICE.

GEORGE CODE, OF MELROSE, MASSACHUSETTS, ASSIGNOR, BY MESNE ASSIGNMENTS, OF ONE-HALF TO WALTER B. PELTON, OF BOSTON, MASSACHUSETTS.

STEAM-TURBINE.

SPECIFICATION forming part of Letters Patent No. 759,420, dated May 10, 1904.

Application filed August 6, 1902. Renewed October 7, 1903. Serial No. 176,152. (No model.)

To all whom it may concern:

Be it known that I, GEORGE CODE, of Melrose, in the county of Middlesex and State of Massachusetts, have invented certain new and useful Improvements in Steam-Turbines, of which the following is a specification.

This invention has for its object to provide a simple and perfectly-balanced steam-turbine of the class in which steam passes radially from the center to the periphery of the turbine; and it consists in the improvements which I will now proceed to describe and claim.

Of the accompanying drawings, forming a part of this specification, Figure 1 represents a sectional view of my improved turbine, the plane of the section being lengthwise of the axis. Fig. 2 represents a section on line 2 2 of Fig. 1. Fig. 3 represents a view similar to Fig. 1, showing a modification. Fig. 4 represents a section on line 4 4 of Fig. 3.

The same reference characters indicate the same parts in all the figures.

In the drawings, *a* represents the shaft of the turbine, to which is affixed the hub *b* of the turbine body or disk *b'*, said disk being preferably a solid metal plate slotted for the reception of the turbine blades or buckets hereinafter described. The casing in which the said wheel and its buckets rotate is composed of two parallel side plates *c c*, separated by a space or chamber *d* and a suitable cylindrical confining wall or curb *e*, which forms the inclosing wall of said chamber and is bolted to the margins of the plates *c c*. The plates *c c* are provided with central outwardly-projecting enlargements *c' c'*, which contain annular steam spaces or chambers *c*², communicating with the inner portion of the chamber *d*. Steam is admitted to the chambers *c*² through suitable inlet-pipes *f f*, the steam passing from the chambers *c*² outwardly into the chamber *d*, as indicated by the arrows in Fig. 1.

The plates *c c*, their enlargements *c' c'*, and the confining wall or curb *e* constitute the casing of the turbine, and the inner substantially cylindrical walls *c' c'* of the enlargements *c' c'*, which closely surround the shaft

a and hub *b*, serve to protect or shield the latter from the action of the live steam, which enters the chambers *c*² from the pipes *f f*. 50 Practically, therefore, the chambers *c*² constitute live-steam ports in the casing, which ports are entirely separated from the wheel-shaft space.

The wheel or disk *b'* is provided with blades 55 or buckets *g*, which project at equal distances from the opposite sides of the disk *d'* into the subdivisions of the chamber *d*, formed by said disk. Each blade is preferably formed by inserting a thin strip of metal 60 into a slot formed through the disk *d'*, the blades and slots being tangentially arranged, as shown in Fig. 2. There are two or more annular series of blades, three series being shown in the present instance, each annular 65 series being separated from the next by an annular space.

The casing is provided with flanges *h*, suitably affixed to the side plates *c c* and projecting into the spaces between said side plates and the 70 disk *d'*, said flanges alternating with the blades or buckets *g*. In the flanges *h* are formed tangential ports or steam-guides *h'*, the angle of these ports being opposite to that of the blades *g*, as shown in Fig. 2. The outer surface of 75 each flange *h* is in close proximity to the inner edge of a series of blades *g*, and between the outer edges of the blades of each series and the next flange *h* is an annular steam-space *i*. 80

It will be seen that the steam passing from the central chambers *c*² outwardly into the chamber *d* is given a tangential direction by the first series of ports or guides *h'* and is caused to strike the blades *g* of the first series 85 substantially at right angles with the inner faces of said blades, steam passing outwardly into the first space *i* and being then deflected as before by the second series of ports *h'* and directed against the second series of blades, and 90 so on until the steam enters the outer space *i*, from which the exhaust-steam escapes through an outlet-passage *m*.

It will be seen that the successive increase

in the diameter of each flange h and series of blades g from the center outwardly provides for an efficient expansive action of the steam as it passes from the center to the margin of 5 the chamber d . Furthermore, the annular spaces or chambers i between the different series of ports and blades permits the steam to expand in said chambers, so as to equalize the pressure through the ports or steam-guides 10 surrounding said spaces or chambers. Hence I obtain the maximum efficiency and economy 15 in the employment of the steam.

In Figs. 3 and 4 I show a modification in 15 which the spaces i between the flanges h and the blades g are omitted, the inner edges of 20 the blades g being in close proximity to the outer edges of the flanges h , so that the steam passes directly from the outer edge of each series of buckets or blades into the next series 25 of ports.

The location of the wheel at the center of 25 the steam-chamber, so that it partially subdivides said chamber, together with the employment of alternating blades and guides at 30 opposite sides of the wheel, causes a balancing action and greatly increases the effectiveness.

I claim—

1. A steam-turbine having fixed ports or guides arranged in annular series, and a shaft 30 having blades arranged in annular series alternating with the fixed ports, annular expansion and equalizing chambers being formed between the ports and blades.

2. A steam-turbine comprising a casing having an annular steam-chamber, a shaft journaled in said casing and having a wheel or disk located in and partially subdividing said chamber, fixed inwardly-projecting annular flanges inside the casing at opposite sides of 40 the wheel and having tangential ports or guides, and annularly - arranged tangential blades projecting from opposite sides of the wheel and alternating with said guides, said blades being separated from the port-flanges 45 to form expansion and equalizing chambers between the port-flanges and blades.

In testimony whereof I have affixed my signature in presence of two witnesses.

GEORGE CODE.
